UNITED STATES PATENT OFFICE

2,455,680

BUFFING WHEEL

Nathan Kaplan, Freehold, N. J.

Application September 12, 1946, Serial No. 696,468

6 Claims. (Cl. 51—193)

1

This invention relates to new and useful improvements in buffing wheels.

Heretofore it has been customary to build up buffing wheels upon the shafts of buffing machines by placing spacer washers and felt discs alternately in position. On a machine requiring a wide buffing wheel, the time consumed in mounting the discs and washers in position is about three and one half hours.

It is an object of this invention to construct a buffing wheel section which includes a unit of spacer washers and felt discs. By using these units it is possible to mount them upon the shaft of a buffing machine in about one half hour's time. Obviously an important advantage of the buffing wheel unit is the saving of time in mounting them in position on a machine.

Moreover, present day buffing wheels built up from felt discs and spacer washers wear out in a relatively short period of time. They also wear out unevenly, which is objectionable. This invention proposes the construction of a buffing wheel which will have a longer life than present day similar wheels and which will wear out more evenly which further adds to its life.

More specifically the invention proposes to characterize the new and improved buffing wheel by the fact that it includes annular felt sections spaced from each other and cloth faced cork sections between and spaced from the felt sections. The cork sections with the cloth facings are stiffer and more durable than the felt sections. They serve to support the felt sections and in this way prolong the life of the buffing wheel. Moreover, cork material is known to be excellent for buffing. It has numerous pores which hold the grease and polish. This is desirable. I have discovered that thin cork sections were too fragile and entirely unsatisfactory. I have further discovered that thin cork sections could be used provided they were laminated with cloth. It is for this reason that they are provided with facings of cloth. When thus constructed they are highly durable and a far superior buffing wheel is produced.

The invention also proposes that the felt sections and cork sections be provided with radial slots extending inwards from their peripheries and dividing off arcuate portions to add to the flexibility of the buffing wheel.

It is another object of this invention to secure the felt sections and the cork sections together with fastening elements to produce a unit previously referred to. The fastening elements may comprise rivets.

2

Another object of this invention is to provide each buffing wheel, or unit, with a spacer element mounted on one face for spacing the first section and last section of adjacent similar units when they are mounted on the shaft of a buffing machine.

The invention contemplates a modified form in which the felt and cork sections are of different designs and constructions.

Another object of the invention is the construction of a device as described, which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

10 20 In the accompanying drawing forming a material part of this disclosure—

Fig. 1 is a perspective view of a buffing wheel constructed in accordance with this invention.

25 Fig. 2 is a fragmentary enlarged vertical sectional view taken on the line 2—2 of Fig. 1.

Fig. 3 is a fragmentary enlarged detailed view of one of the cork sections shown in Fig. 2.

30 Fig. 4 is a fragmentary sectional view similar to Fig. 2 but illustrating a modified form of buffing wheel.

The buffing wheel, in accordance with that form of the invention illustrated in Figs. 1 to 3 inclusive, includes annular felt sections 10 spaced from each other and cork sections 11 between 35 and spaced from the felt sections 10. Spacing washers 12 are engaged between the sections 10 and 11 for holding them in their spaced relationship. A spacing washer 12 is also mounted on the outer face of one of the end sections for 40 spacing this section from the adjacent section of a similar buffing wheel. Fastening elements, such as rivets 14, are engaged through the spacing washers 12 and the sections 10 and 11 for holding them in a unit.

45 Each cork section 11 comprises a central disc section 15 of cork and cloth laminations 16, or cloth facings 16 pasted or cemented together. The cloth facings 16 may comprise muslin or similar cloth material. For an eight inch buffing 50 wheel the felt sections 10 and cork sections 11 may be one-sixteenth inch thick. The felt sections 10 and cork sections 11 are provided with radial slits 27 extended inwards from their peripheries and diving off portions 28 so as to make 55 the buffing wheel more flexible. In lieu of cork

sections it is feasible to use fiber or, fibrous sections which may be cloth faced, if desired.

In Fig. 4 a modified form of buffering wheel has been disclosed which also includes felt sections 20 spaced from each other and cork sections 21 between and spaced from the felt sections 20. The felt sections 20 and cork sections 21 are annular, or ring-like in shape. They are mounted on fiber annular support members 23. The fiber support members 23 have flanges 24 for keeping them properly spaced from each other. Fastening elements, or rivets 25 engage through the flanges 24. The felt sections 20 and cork sections 21 are cemented upon the peripheral edge portions of the support members 23 and are also secured in position with lines of stitches 26. The cork sections 21 comprise central cork portions and cloth facings similar to the detailed disclosure shown in Fig. 3.

The operation and use of the new and improved buffering wheel may be understood from the following:

It should be noted that the buffering wheel comprises a unit of disc-like sections. These units may be readily mounted on the shaft of a buffering machine for building up a buffering element of any desired width. Mounting the units on the shaft of the buffering machine is very much faster than mounting felt discs and spacing washers, as is now the case. The new buffering wheel will be more durable than present day buffering wheels because the cork sections 21, or fiber sections, will support the felt sections 20. Moreover, the cork sections make excellent buffering sections. The pores in the cork will hold the grease and polish.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. The combination in a buffering wheel having means for holding annular sections in spaced positions, of annular felt sections spaced from each other, and cork sections having cloth facings between said felt sections.

2. The combination in a buffering wheel having means for holding annular sections in spaced positions, of annular felt sections spaced from each other, and cork sections between and spaced from said felt sections, said cork sections being faced with cloth facings.

3. A buffering wheel comprising annular felt sections spaced from each other, cork sections between and spaced from said felt sections, and fastening elements fixedly connecting said sections together as a unit, said unit having a spacing element mounted on one face for spacing the first section from the last section of an adjacent similar unit.

4. A buffering wheel, comprising annular support members fixedly connected together in a unit, and annular felt sections and annular cork sections with cloth facings mounted upon the peripheral portions of said support members and spaced from each other.

5. A buffering wheel, comprising annular support members fixedly connected together in a unit, and annular felt sections and annular cork sections mounted upon the peripheral portions of said support members, said cork sections being cloth faced.

6. The combination in a buffering wheel, having means for holding annular sections in spaced positions, of annular felt sections spaced from each other, and laminated cloth and cork sections between and spaced from said felt sections.

NATHAN KAPLAN.
